UNITED STATES PATENT OFFICE.

PAUL A. STOVER, OF RACINE, WISCONSIN, ASSIGNOR TO THE STOVER SIGNAL ENGINEERING CO., OF RACINE, WISCONSIN, A CORPORATION OF DELAWARE.

DESIGN FOR A DIRECTIONAL SIGNAL.

Application filed April 11, 1927. Serial No. 21,542. Term of patent 3½ years.

To all whom it may concern:

Be it known that I, PAUL A. STOVER, a citizen of the United States, residing at Racine, in the county of Racine and State of Wisconsin, have invented a new, original, and ornamental Design for a Directional Signal, of which the following is a specification, reference being made to the drawing

forming a part thereof, in which the figure is a perspective view of a directional signal showing my new design.

I claim:

The ornamental design for a directional signal substantially as shown.

PAUL A. STOVER.
